UNITED STATES PATENT OFFICE.

MARIUS LATOUR, OF PARIS, FRANCE, ASSIGNEE TO LATOUR CORPORATION, OF JERSEY CITY, NEW JERSEY, A CORPORATION OF DELAWARE.

ELECTRICAL APPARATUS.

No Drawing. Application filed August 19, 1921, Serial No. 493,662, and in France May 20, 1915.

(GRANTED UNDER THE PROVISIONS OF THE ACT OF MARCH 3, 1921, 41 STAT. L., 1313.)

Different arrangements have been suggested for doubling or trebling the frequency of single or polyphase alternating currents. Heretofore, this has been accomplished by 5 making use of the phenomenon whereby the iron cores in the magnetic circuits of the transformers or self induction coils are saturated, the said circuits being permanently magnetized by direct currents.

10 As a matter of fact, if the curve illustrating the magnetization of iron is studied it will be found that the phenomenon of the multiplication of the frequency is not appreciable unless there is a sufficiently large variation in the flux produced by the primary alternating current about the point representing the permanent direct current magnetization. This variation will be e. g. 2000 to 4000 gauss for high frequencies, 10000 to 20000 periods or more; being used in wireless telephone and telegraph apparatus. From the standpoint of iron losses, this variation will only give one half of this as a true inductive change, i. e., the variation will be 25 from 1,000 to 2,000 gauss.

On the other hand, it has been proved that from the standpoint of iron losses, in ordinary transformers it is advisable to reduce the utilized magnetic induction in proportion with the increase in the frequency. For 30 very high frequencies, 20000 periods or more, preferably very low magnetic inductions should be employed, the maximum being a few hundred gauss.

35 The multiplication of comparatively high frequencies can not be efficiently effected with the employment of ferrous core transformers owing to the large magnetic induction variations required resulting in excessive iron loss at the comparatively high frequencies.

In accordance with the present invention, the multiplication of such relatively high

45 frequencies is efficiently effected by the utilization of magnetic materials saturating at a considerably lower magnetic induction than ferrous cores and also possessing considerably lower losses than ferrous cores at high frequencies.

Nickel answers these requirements. The 50 induction variation that is necessary for effecting therein the phenomenon of frequency multiplication is approximately three or four times less than in case of ferrous cores resulting in considerably smaller core losses.

55 The nickel may be alloyed with any substance suitable for accentuating the elbow made by its magnetization curve, or for increasing its resistivity to reduce the Foucault currents, or even for decreasing its permeability.

60 As in the case of iron, the resistivity may be increased by the use of silicon.

65 The properties of the nickel may be improved by subjecting it to a mechanical influence, such as tension, compression or torsion.

70 It should be understood, that the metal must be used in the thinnest possible sheets.

Having described my invention, what I 75 claim is:

1. In apparatus for distorting the wave form of high-frequency alternating currents having a magnetic circuit and means for cyclically supersaturating it, a magnetic circuit comprising substantially all nickel.

75 2. In high-frequency apparatus relying upon the phenomenon of magnetic saturation for its operation and having a magnetic circuit and means for cyclically supersaturating it, a magnetic circuit comprising substantially all nickel and containing silicon adapted to increase the sharpness of the saturation bend.

MARIUS LATOUR.
